PUSH TOY

Paul S. Bolger, Forest Hills, N.Y.

Application May 20, 1955, Serial No. 509,858

4 Claims. (Cl. 46—107)

This invention relates to a child's toy and more particularly to an action push toy which when pushed is actuated to simulate animation.

Push toys generally include ground contacting rotary means such as wheels and a push rod for moving and guiding the wheels. Usually means are also provided for supporting noise or movement producing mechanisms on the axle of the wheels. Such means require additional parts and increase the cost of producing the toy and also frequently such toys are properly operable only when pushed from one side of the axle. Small children are generally not very discerning and therefore will sometimes seek to push the toy when the rod is on the wrong side with the result that the toy will not operate properly, if at all, and may be permanently damaged.

Furthermore, the push rod is not employed other than as a means of propelling the device.

In devices in which the push rod has been utilized to support movable elements and in which the toy might be operated by pushing from either side of the axle no means have been provided for orienting the elements to face in a forward direction in all cases. Also, such devices have not included a plurality of separate slidable and rotatable elements which provide noise by contact with each other as they slide up and down the push rod and provide increased animation by rotating independently of each other.

It is an object of this invention to provide a push toy in which the elements are so arranged that regardless of which side of the axle the push rod is disposed, the toy will be operable.

A further object is to utilize the push rod for supporting movable elements of the toy which are free to slide and rotate on the push rod, which elements when assembled, by sliding together at the lower end, form a simulated figure.

Another object is to provide means by which the elements of the push toy will properly orient themselves when the push toy is in operation regardless of which side of the axle the push rod is disposed so that a child may enjoy the toy without assistance in properly orienting the push rod with respect to the axle.

The invention comprises a toy having spaced ground-contacting wheels connected by an axle, a push rod, means for connecting the push rod to the axle, at least one member slidably and rotatably mounted on the push rod, cam means on the axle for slidably and rotatably actuating said member and means for orienting said member with respect to the direction in which the toy is pushed. The member may be eccentrically weighted with respect to the axis of the push rod and the portion of the element which is to be oriented in the direction in which the toy is pushed disposed on the side of the element diametrically opposed to the heavier side of the element. As the toy is pushed, the push rod is held at a slight angle and the heavier side of the element moves to the under side so that the portion which is to be oriented in the direction in which the toy is pushed comes to the upper side of the rod. The invention also contemplates mounting more than one member slidably and rotatably on the push rod, one member above the other; the members being shaped to form the

2

component parts of a simulated figure such as a clown; the elements being independently slidable and rotatable so that as they are actuated by the cam means and are pushed upward and rotated independently, they simulate jumping and dancing actions of a rollicking clown or other figure.

For a more complete description of one embodiment of the invention, reference is made to the drawings wherein:

Fig. 1 is a front perspective view of the toy;

Fig. 2 is a sectional view taken along the line 2—2 in Fig. 1; and

Figs. 2a and 2b show partial sectional detail views of alternate forms of the head element.

The toy shown in the drawings includes spaced ground-contacting wheels 12 which may be fixed on an axle 11. A push rod 10 is connected to the axle by an element such as eye bolt 20, or other suitable means for loosely connecting the push rod and forming a bearing for the axle.

Eccentric cams 13 are mounted on the axle 11 on both sides of the push rod 10. Elements 15 may be slidably mounted on the push rod 10. These members may take any desired form; for example, as shown in the drawings of the elements 15, they define or constitute three sections of the trunk of a clown figure. The lowermost element 15 being provided with leg members 21 at the outer ends of which are positioned beads or rounded members 22 giving the stylized effect of legs and feet for the clown. The uppermost of the three elements 15 constituting the trunk of the clown may be provided with arm elements 17 and stylized hand elements 18 in the form of rounded beads. The clown figure is completed by providing a further element 16 slidably mounted on the push rod 10 on which the face of a clown is painted as shown in Fig. 1. It will be appreciated that any desired arrangement of elements to amuse or interest a child may be positioned in the sliding arrangement shown on the push rod 10.

A knob or pushing handle such as the rounded member 23 may be fixed at the upper end of the push rod 10, as shown in Fig. 1. Knob 23, in addition to providing a convenient means for holding and guiding the push toy, also serves to retain the slidable elements 15 and 16 on the push rod; the elements 15 and 16 being free to slide up and down the push rod either separately or together, there being no connection between these elements.

In operation, the child grasps the knob 23 and pushes the toy forward causing the ground-contacting wheels 12 to rotate. The wheels 12 cause the axle 11 and the cams 13, fixed to the axle, to rotate. The cams which are eccentrically mounted, as best shown in Fig. 2, turn with the axle 11, on eccentric axes, causing the elements 15, 16 to undulate, sliding upward and downward along the push rod 10. If the push toy is rolled quite rapidly, the elements 15 and 16 will be caused to jump higher on the push rod 10. The effect of the cam action is to produce a jumping of the clown and produces a noise as the various elements 15 and 16 forming the clown's body and head collide with each other moving up and down the push rod.

In addition to the cam members causing the clown elements to jump up and down on the push rod, there is a tendency for one or the other of the cams to impart a rotary motion to the lower element 15. This may result in part from the fact that the push rod 10 may be tilted slightly out of its perpendicular relationship to the axle 11 or by arranging the eccentricity of the cams out of phase with each other. The rotary motion and the jumping motion impart to the clown figure the pleasing animated effect of a rollicking clown.

In previous devices in which an element has been slidably mounted on the push rod for reciprocatory actuation and in which it was desired to have the elements maintain a selected orientation with respect to the axis of the push rod, means have been required such as a

key for the slidable element and a longitudinal keyway on the push rod. It will be appreciated with provision of such means to retain the desired orientation that the elements would not be able to rotate freely about the push rod. In this invention, means have been provided to permit selected orientation and at the same time to allow the slidable elements to rotate freely about the push rod. The orientation means comprises weighting any slidable element on one side thereof. In normal operation of the push toy, the push rod will be at an angle to the vertical and the slidable elements on the push rod, being free to rotate, will rotate so that the side which is weighted is on the lower side of the push rod; for example, if it is desired to have the portion of the element 16 on which the face of the clown is depicted disposed in the direction in which the push toy is moving, the weighting means is placed on the portion of the element 16 diametrically opposite to the face portion so that when the push toy is in its normal operating position with the push rod angularly disposed as shown in the side view of Fig. 2, the weighted element will move about the rod 10 to the lower side thereof bringing the face portion of the element 16 to the upper side of the push rod 10 thereby orienting the clown's face in the direction in which the push toy is moved.

As shown in the drawings, the weighting means may be any suitable element such as a small metal bell 19 shown in Fig. 2 attached to the exterior of the element 16. The weighting means may also consist of a weight embedded in the element or the element itself may be eccentrically bored, so that the differential in weight between portions of the element with respect to the axis of the push rod will result in the desired weighting of one portion of the slidable element with respect to a diametrically opposite portion of said element as shown in Figs. 2a and 2b respectively.

It will be appreciated that with the orientation means described above, the slidable element is free to rotate about the push rod and the face portion of the slidable member is properly oriented regardless of the direction in which the push toy is moved. Furthermore, with this means of orientation, there is no additional friction which would be present in a device in which the slidable element was keyed in a keyway provided in the rod. Furthermore, with such a key arrangement, the element could only orient in one direction and could not turn to face in the other direction when the toy was pushed in the second direction. With the orienting means of this invention, the face will be oriented for either direction.

It will be appreciated that the cam elements which are connected to the axle may have any desired configuration to actuate the slidable elements. It has been found desirable however in order to obtain the greatest amount of movement to provide cams in which there is a maximum of eccentricity so that the slidable elements will move from a point close to the axle to a point as remote from the axle as possible. As shown in the drawings, the cams have one maximum and one minimum position in each cycle and the transition from the two extreme positions is rather gradual. More than one maximum position can be provided and the transition between the maximum and minimum positions may be quite abrupt in which case the action of the toy elements will be noisier and more rapid.

It will be noted that the cams 13 are disposed so as to prevent the bearing connection 20 from sliding laterally along the axle 11 during operation of the toy.

Any suitable materials may be used in the fabrication of the various elements of the toy. The various parts may be fabricated of wood, plastic and metal, or other suitable materials. It should also be noted that the leg and arm elements 21 and 17 respectively may be made of flexible plastic or rubber and the hand and foot ele-

ments 18 and 22, respectively, may be suitable noise-making devices such as bells or claque to increase the noise making potential of the device.

It will be appreciated that the invention described above fulfills the objects of providing a push toy in which the elements are so arranged that regardless of which side of the axle the push rod is disposed on the toy it is operable and the movable elements may be actuated regardless of which direction the toy is pushed. It will also be appreciated that the invention fulfills the object of providing means by which the elements of the push toy may properly orient themselves when the push toy is operated in either direction so that a child may enjoy the toy without assistance in orienting the elements.

In addition, the toy of this invention has the advantage of providing elements which because they are separate and free to rotate as well as slide on the push rod, can produce toy figures such as clowns which are capable of great activity, and therefore, serve more aptly to simulate the amusing gestures and attitudes of the figures which the combined movable elements represent.

In accordance with the provisions of the patent statutes, I have herein described the principle of operation of the invention, together with the elements which I now consider the best embodiments thereof, but I desire to have it understood that the structure disclosed is only illustrative and the invention can be carried out by other means. Also, while it is designed to use the various features and elements in the combinations and relations described, some of these may be altered and modified without interfering with the more general results outlined.

Having thus described my invention, I claim:

1. A push toy comprising spaced ground-contacting wheels, an axle connecting said wheels, a push rod, bearing means connected to one end of said push rod, said axle being rotatable in the bearing means, at least one element slidably and rotatably mounted on said push rod, cam means on said axle adjacent the push rod for slidably and rotatably actuating said element, means for weighting one side of said element, the diametrically opposite side being provided with suitable visual indicia, whereby said element will be oriented, with the side diametrically opposite said weighting means uppermost when said push rod is angularly disposed in operating position so that the indicia is facing in the direction in which the toy is pushed.

2. The push toy of claim 1 wherein the weighting means comprises means connected to one side of said slidable element.

3. The push toy of claim 1 wherein the weighting means comprises defining the rod-receiving bore in said slidable element eccentrically with respect to said element.

4. A push toy comprising spaced ground-contacting wheels, an axle connecting said wheels, a push rod, bearing means connected to one end of said push rod, the bearing means being rotatably mounted on said axle, more than one element each being separately slidably and rotatably mounted on said push rod, cam means on said axle on both sides of the said bearing connection with said axle and in the path of said slidable and rotatable elements for defining the location of the bearing means and for contacting said slidable and rotatable elements for slidably and rotatably actuating said elements, along said push rod.
